ADJUSTING MEANS FOR SLIDABLE
SIDE JAW WRENCHES

Fray Alejandro Calbo Alemany, Cheva, Spain

Application August 4, 1951, Serial No. 240,364
In Spain September 7, 1950

2 Claims. (Cl. 81—175)

1

The present invention relates to wrenches, and is particularly directed to improvements in the adjusting mechanism for a slidable side jaw wrench.

An object of the present invention is to provide a wrench of the described character wherein the relative movements of the jaws are positively effected by manual actuation for both closing and opening of the space or span between the jaws.

Another object is to provide a wrench of the described character wherein the use of a spring element to provide for relative movement of the jaws in one direction is avoided, so that the useful operating life of the wrench is not limited by fatigue of a spring element.

Another object is to provide a wrench of the described character wherein the jaws are movable to each other in instantaneous response to adjustments effected by the user of the wrench, and the jaws retain their adjusted relative positions without excessive play.

Further, it is an object of the present invention to provide a wrench of the described character which is simple in construction and relatively inexpensive to produce, and wherein the parts can be easily assembled or disassembled.

In accordance with the present invention, the above and other objects, features and advantages are achieved by providing a wrench having a fixed jaw and a movable jaw mounted for movement toward and away from the fixed jaw. A threaded spindle is mounted for rotation about an axis at a substantial angle to the direction of movement of the movable jaw and for axial displacement in response to the rotation of the spindle. The present invention provides an arrangement for converting the axial movements of the spindle into movement of the movable jaw toward and away from the fixed jaw and this arrangement comprises a guide surface on the movable jaw at a substantial angle to the axis of the spindle, a head on the spindle formed to bear against the guide surface when the spindle is moved axially in one direction for displacing the movable jaw in one direction relative to the fixed jaw, a slot formed in the movable jaw parallel to the guide surface and opening longitudinally at the latter through a channel of reduced width, an extension projecting axially from the head of the spindle and extending loosely through the channel of reduced width and into the slot, and an enlargement on the end of the axial extension within the slot and having a width greater than the channel so

2

that, when the spindle is moved axially in the opposite direction, the enlargement will bear in said slot for displacing the movable jaw in the opposite direction relative to the fixed jaw. Further, in accordance with the present invention, the extension preferably has a length slightly greater than the depth of the channel and the clearance between the slot and the enlargement is greater than the difference between the length of the extension and the depth of the channel so that the engagement of the head with the guide surface and the engagement of the enlargement with the surface of the slot is alternative to minimize the frictional resistance to movement of the movable jaw.

In order that the invention may be fully understood, an illustrative embodiment thereof is hereinafter described in detail and shown in the accompanying drawings, wherein:

20 Fig. 1 is a side elevational view of a slidable side jaw wrench embodying the present invention;

25 Fig. 2 is a vertical sectional view of the wrench of Fig. 1 viewed from the side and with a spindle element thereof shown in elevation;

Fig. 3 is a fragmentary, transverse sectional view taken along the line 3—3 of Fig. 2; and

Fig. 4 is an enlarged detail of a portion of the structure shown in Fig. 3.

30 Referring to the drawing in detail, it will be seen that the slidable side jaw wrench 10, having adjusting mechanism embodying the present invention, includes a fixed jaw 11 integral with the head 12 of the wrench at one end of the wrench handle 13. A transverse opening or channel 14 extends through the head 12 of the wrench below the fixed jaw 11, and inwardly directed guide ridges or rims 15 extend along the opposite sides of the top of the opening or channel 14 and are inclined relative to the longitudinal axis of the handle 13. A movable jaw 16 is arranged for movement toward and away from the fixed jaw 11 and has a lower portion extending into the channel 14. The lower portion of the movable

40 jaw 16 is formed with grooves in its opposite side faces receiving the guide ridges 15 (Fig. 3) so that the latter guide the movements of the movable jaw relative to the fixed jaw. The handle 13 is formed with a longitudinal slot 17 opening at the opposite sides of the handle and having guides 18a and 18b along the opposite longitudinal edges thereof. A threaded bore 19 extends longitudinally in the handle and opens at its opposite ends into the channel 14 and the slot 17. A spindle 20 50 is disposed in the handle and includes an upper

threaded portion 21 of relatively small pitch threadably engaging in the bore 19, and a lower threaded portion 22 of relatively large pitch which extends longitudinally in the slot 17. A nut 23 is threaded on the lower portion 22 of the spindle 20 and is manually movable along the slot 17. The nut 23 is formed with suitable grooves in its opposite edges to slidably receive the guides 18a and 18b so that the latter prevent rotation of the nut 23 while permitting axial movement of the latter. In order to permit assembly of the nut 23 on the lower portion 22 of the spindle, the end of slot 17 remote from the threaded bore 19 is enlarged, as at 24, and, after such assembly, a pin 25 is extended across the enlarged end of the slot to prevent inadvertent removal of the nut 23 from the threaded lower portion 22 of the spindle. It is apparent that movement of the nut 23 along slot 17 will cause rotation of the spindle 20 and that the engagement of the upper threaded portion 21 of the spindle 20 in the threaded bore 19 will convert the rotation of the spindle into axial movement of the latter relative to the handle 13 so that the upper end of the spindle 20 will be made to project, more or less, into the channel 14 in the head of the wrench.

In accordance with the present invention, the mechanism for converting the axial movements of the spindle 20 into movement of the movable jaw 16 toward and away from the fixed jaw 11 includes a head 26, which may have a conical upper surface, formed on the upper end of the spindle 20 to engage upwardly against a guide surface 27 formed on the lower edge of the movable jaw 16 at a substantial angle to the axis of rotation of the spindle so that, as the spindle moves upwardly, the head 26 bears against the inclined guide surface 27 and causes movement of the jaw 16 toward the fixed jaw 11, that is, toward the left as viewed in Figs. 1 and 2. The lower portion of the movable jaw 16 is formed with a slot 28 parallel to the guide surface 27. The slot 28 is preferably of cylindrical configuration and opens along its length at the guide surface 27 through a channel 29 of reduced width, that is, having a width substantially smaller than the diameter of the cylindrical slot 28. A rod or extension 30 projects axially upward from the head 26 and extends loosely through the channel 29 of reduced width into the slot 28. An enlargement 31 is formed on the end of the extension 30 within the slot 28 and has a diameter greater than the width of the channel 29 so that the enlargement 31 can be removed from the slot 28 only at the ends of the latter. Thus, when the spindle 20 is moved downwardly, the enlargement 31 bears downwardly on the surface of the slot 28 and causes the jaw 16 to move in the direction away from the fixed jaw 11, that is, toward the right as viewed in Figs. 1 and 2.

As seen in Fig. 4, the extension 30 has a length which is greater than the depth of the channel 29 by a distance indicated by the letter d_1 , and the diameter of the cylindrical slot 28 is greater than the diameter of the enlargement 31 by a distance indicated by the letter d_2 . In accordance with the present invention, the distance d_2 is preferably greater than the distance d_1 so that, when the enlargement 31 engages the lower surface of slot 28, the head 26 is out of engagement with the guide surface 27 and, when the head 26 engages the guide surface 27, the enlarge-

ment 31 is centered in the slot 28 thereby minimizing the frictional resistance to movement of the jaw 16 toward and away from the fixed jaw 11.

From the foregoing, it is apparent that the adjusting mechanism for a slidable side jaw wrench embodying the present invention effects positive movement of the movable jaw 16 both toward and away from the fixed jaw 11 in response to axial displacement of the spindle 20.

While I have described and shown an illustrative embodiment of my invention, it is to be understood that the invention is not limited to this precise embodiment and that various changes and modifications may be made therein without departing from the spirit or scope of the invention as defined in the appended claims.

What I claim is:

1. In a slidable side jaw wrench having a fixed jaw, a movable jaw mounted for movement toward and away from the fixed jaw, and a threaded spindle mounted for rotation about an axis at a substantial angle to the direction of movement of the movable jaw and for axial displacement in response to the rotation thereof; an arrangement for converting the axial movements of the spindle into movement of the movable jaw toward and away from the fixed jaw comprising a guide surface on the movable jaw at a substantial angle to the axis of rotation of the spindle, a head on the spindle formed to bear against said guide surface when the spindle is moved axially in one direction for displacing the movable jaw in one direction relative to the fixed jaw, a slot formed in the movable jaw parallel to said guide surface and opening longitudinally at the latter through a channel of reduced width, an extension projecting axially from said head of the spindle and extending loosely through said channel of reduced width and into said slot, and an enlargement on the end of said extension within said slot and having a width greater than said channel so that, when the spindle is moved axially in the opposite direction said enlargement will bear in said slot for displacing the movable jaw in the opposite direction relative to the fixed jaw.

2. In a slidable side jaw wrench; the arrangement according to claim 1, wherein said extension has a length slightly greater than the depth of said channel and the clearance between said slot and said enlargement is greater than the difference between said length of the extension and said depth of the channel so that the engagement of said head with said guide surface and the engagement of said enlargement with the surface of said slot is alternative.

FRAY ALEJANDRO CALBO ALEMANY.
